UNITED STATES PATENT OFFICE.

SIGISMUND M. MICHELSON, OF MILWAUKEE, WISCONSIN.

TRUNK-TRAY.

SPECIFICATION forming part of Letters Patent No. 278,994, dated June 5, 1883.

Application filed March 27, 1883. (No model.)

To all whom it may concern:

Be it known that I, SIGISMUND M. MICHELSON, of Milwaukee, in the county of Milwaukee, and in the State of Wisconsin, have invented 5 certain new and useful Improvements in Trunk-Trays; and I do hereby declare that the following is a full, clear, and exact description thereof.

My invention relates to trunk-trays; and it 10 consists in movable folding legs attached thereto, as will be more fully set forth herein-after.

In the drawings, Figure 1 is a perspective view of an open trunk, showing the top tray 15 partly raised and supported in that position by movable legs. Fig. 2 is a view of a tray wholly removed from a trunk and supported upon four movable folding legs. Fig. 3 is a view of a tray provided with two legs, and 20 supported thereon by resting one edge of the tray upon a corner or edge of the open trunk. Fig. 4 is a view of a tray with its legs folded and in position for the tray to be replaced within the trunk; and Figs. 5 and 6 are details 25 of the legs and of the castings whereby they are secured to the trays.

A represents a trunk of ordinary construction provided with the trays B B, and to these trays are attached the movable folding legs C, 30 which may be of any desired number, but preferably either two or four to each tray.

D are metallic castings, the preferred form of which is shown in detail in Figs. 5 and 6, the said casting consisting of a plate, d, having 35 holes to permit of its ready attachment, by screws or otherwise, to the sides or ends of the trays, and a box or housing, d', cast with the said plate and open on one side, as shown.

The legs C are preferably of wood, and may 40 either extend all the way into said housings, or they may be bolted to a shank, C', of wood or metal, (preferably the latter,) which is secured within the housing by a pivot or bolt, d', on which it freely swings. The housings 45 being open at their inner sides, the legs will be permitted to fold freely inward, while the solid outer sides of the housings will prevent them from spreading out too far, so that when the tray is removed the said legs will at once

drop down and form a solid support for the 50 tray. In Fig. 1 I have shown a simpler form of leg, being one merely pivoted to the end of the tray, and a pin or stop, b, serves to limit the outward movement of the leg. This will answer for the cheaper class of trunks; but for 55 those of more costly construction I prefer to employ the castings D, already described, instead of the stop b. In this view I have shown the top tray tilted up, but not wholly removed, and its legs C rest against pins or 60 notches c in the top surface of the ends of the tray or support beneath. This will enable one to obtain convenient access to articles in either the top tray, or in the tray or trunk beneath the same, without wholly removing the said 65 top tray, and is of itself a very convenient feature; but the most valuable feature of my invention lies in the convenient manner in which the trays may be disposed about the trunk in packing or unpacking. Heretofore 70 trunk-trays have usually either been placed upon the floor, necessitating continual stooping over them, or else placed upon a chair, bed, or other article of furniture, thus taking up much room, and being frequently in the 75 way, whereas with my movable legs they may be either grouped about the trunk, resting partially thereon, as shown in Fig. 3, or else converted into independent stands, as in Fig. 2, and in either case they will be sup- 80 ported firmly, and with very little danger of being accidentally upset, while their elevation from the floor is at the height most convenient for access. Those trays having four legs can be as conveniently rested against the 85 angle of the trunk-frame as can the two-leg trays shown in Fig. 3, because the legs not used can be conveniently folded against the side, as shown in Fig. 4, and the trunk-frame will keep them from dropping down and get- 90 ting in the way.

Having thus described my invention, what I claim as new, and desire to secure by Letters Patent, is—

1. An independent detachable trunk-tray 95 provided with folding legs secured to the outer sides or ends of the tray, with stops or housings to limit their outward spread, and adapt-

ed to fold along the outside of the tray, free from the bottom, substantially as set forth.

2. In combination with a trunk-tray, the housings D, secured thereto, and the folding legs C, pivoted in said housings, substantially as set forth.

In testimony that I claim the foregoing I

have hereunto set my hand, on this 20th day of March, 1883, in the presence of two witnesses.

SIGISMUND M. MICHELSON.
